US0D1036257S

(12) **United States Design Patent** (10) Patent No.: **US D1,036,257 S**
(45) Date of Patent: ** Jul. 23, 2024

(54) **PACKAGING BAG**

(71) Applicant: **Fuji Seal, Inc.**, Osaka (JP)

(72) Inventors: **Yuya Watabe**, Osaka (JP); **Toshio Ishiki**, Osaka (JP); **Asuka Kitani**, Osaka (JP); **Mineyuki Habara**, Osaka (JP)

(**) Term: **15 Years**

(21) Appl. No.: **35/517,352**

(22) Filed: **May 31, 2022**

(80) **Hague Agreement Data**

Int. Filing Date: **May 31, 2022**

Int. Reg. No.: **DM/221684**

Int. Reg. Date: **May 31, 2022**

Int. Reg. Pub. Date: **Jun. 2, 2023**

(30) **Foreign Application Priority Data**

Dec. 2, 2021 (JP) ..... 2021-026484 D

(51) **LOC (14) Cl.** **09-05**

(52) **U.S. Cl.**

USPC **D9/707**; D9/434

(58) **Field of Classification Search**

Primary Examiner — Darcey E Gottschalk

(57) **CLAIM**

The ornamental design for a packaging bag, as shown and described.

DESCRIPTION

1. Packaging bag

1.1 : Front

1.2 : Back

1.3 : Right

1.4 : Left

1.5 : Top

1.6 : Bottom

1.7 : Perspective

The broken lines shown in the drawings represent portions of a packaging bag that form no part of the claimed design; the long dashed and short dashed line indicates only a boundary.

1 Claim, 7 Drawing Sheets
